UNITED STATES PATENT OFFICE.

FRANCIS R. DENNIS AND HARRY W. LEAVITT, OF PEORIA, ILLINOIS.

DESIGN FOR A TRACTOR-HOOD.

53,571.

Specification for Design.

Patented July 15, 1919.

Application filed April 7, 1919. Serial No. 288,390. Term of patent 3½ years.

To all whom it may concern:

Be it known that we, FRANCIS R. DENNIS and HARRY W. LEAVITT, citizens of the United States, residing at Peoria, in the county of Peoria and State of Illinois, have invented a new, original, and ornamental Design for Tractor-Hoods, of which the following is a specification, reference being had to the accompanying drawing, forming part thereof.

Figure 1 is a plan view of a tractor hood illustrating our new design;

Fig. 2 is a side elevation of the same, and Fig. 3 is a front end elevation of the same.

We claim:

The ornamental design for a tractor hood as shown.

FRANCIS R. DENNIS.
HARRY W. LEAVITT.
